DESIGN FOR A BUMPER SUPPORTED GUARD FOR AUTOMOBILES

Joel R. Thorp and Steen Strand, West Allis, Wis.,
assignors to The Fulton Company, West Allis,
Wis., a corporation of Wisconsin

Application December 27, 1937, Serial No. 73,879

Term of patent 3½ years

To all whom it may concern:

Be it known that we, Joel R. Thorp and Steen Strand, citizens of the United States, residing at West Allis, in the county of Milwaukee and State of Wisconsin, have invented a new, original, and ornamental Design for a Bumper Supported Guard for Automobiles, of which the following is a description, reference being had to the accompanying drawing forming part thereof.

In the drawing:

Fig. 1 is an elevation of a bumper supported guard for automobiles, embodying our new design;

Fig. 2 is a top view of the guard; and
Fig. 3 is a side view of the guard.
The dominant or characteristic features of our new design are shown in solid lines.

We claim:

The ornamental design for a bumper supported guard for automobiles, substantially as shown and described.
